UNITED STATES PATENT OFFICE.

JOHN BALTHASAR AND HERMAN GENTZ, OF JERSEY CITY, NEW JERSEY.

AUTOMATIC SAFETY GAS COCK.

Application filed October 1, 1925. Serial No. 59,962.

This invention relates to an automatic safety gas cock.

The primary object of the invention is to provide an automatic latch mechanism for 5 a gas cock or valve which will insure against the unintentional opening of the latter.

A further object of the invention is to provide a latch mechanism of the above mentioned type which may be released by a 10 movement of the operating element in a direction of movement which is convenient to the direction of movement of the valve operating lever or handle, whereby no difficulty will be encountered in operating both the latch and 15 the valve plug with substantially the same movement of the hand.

A further object of the invention is to construct a latch mechanism so that adjustments made to the rotary plug of the valve 20 to compensate for wear will not interfere with the operation of the mechanism.

Other objects and advantages of the invention will be apparent during the course of the following description.

25 In the accompanying drawing forming a part of this specification, and in which like numerals are employed to designate like parts throughout the same,

Figure 1 is a side elevational view of the 30 automatic safety gas cock embodying this invention,

Figure 2 is a top plan view of the same,

Figure 3 is a side elevational view of the 35 rotary plug portion of the valve and its operating lever or handle,

Figure 4 is a transverse sectional view taken upon lines IV—IV of Fig. 1,

Figure 5 is a fragmentary vertical sectional view taken upon lines V—V of Fig. 4, 40 and

Figure 6 shows in plan two different views of a reciprocating plunger member.

In the drawing, wherein for the purpose 45 of illustration is shown a preferred embodiment of this invention, the numeral 5 designates the body portion of this automatic safety gas valve or cock which is formed with the usual or any desired forms of connections 6 and 7. This body portion has extending therethrough the plug bore 8 which is slightly tapered and receives the body 9 of the rotary valve plug 10 therein, the body 9 having a tightening stem 11 which is intended to be surrounded by the compression 50 spring 12 and to have the lock nuts 13 threaded upon its lower end. The valve

body is further provided with the cutout portion 14 within which the movement limiting pin 15 rides for limiting the movement of the plug from a fully opened position to 60 a fully closed position. It will be noted that the pin 15 is normally spaced from the bottom wall of the cutout portion 14 and that this space will permit the body portion 9 of the plug 10 to be adjusted longitudinally of the bore 8 to tighten the plug within the bore should the surfaces of either or both become worn by use.

The valve body 5 has formed thereon a block-like extension 16 which has a bore 17 formed therein and extending from the bore 8 entirely through the block-like extension 16 to the outer face 18 of the same. Figure 6 shows a latch bolt or plunger which includes the cylindrical body portion 19 having the notch 20 formed therein and extending longitudinally thereof and the stem 21 which extends axially from the cylindrical portion 19. Figures 4 and 5 clearly show this plunger 19 as being positioned within the bore 17 and as being urged toward the valve plug 10 by the spiral spring 22 which encircles the stem 21 and is adjustable by the set screw 23 which is threaded in the outer end of the bore 17.

The valve plug 10 is clearly illustrated in Fig. 3 as having formed therein a recess 24 which is elongated in the direction of the length of the plug 10. Figure 4 shows the end of the plunger body 19 as projecting in this recess 24. It will now be understood that when the valve plug 10 is in the position illustrated in Fig. 1, i. e., with the port 25 of the plug arranged at right angles to the gas passageways 26 to shut off the flow of gas through the passageways, the plunger body 19 will automatically enter the recess 24 and prevent the valve plug 10 from being thrown into its gas passing or opened position by the plug operating lever or handle 27. It will be apparent that the elongated nature of the recess 24 will permit the valve plug 10 to be moved longitudinally of the bore 8 of the valve body for taking up wear in the plug or bore and still be positioned or arranged to receive the end of the plunger body 19. The difference in size between the end of the plunger body 19 and the recess 24 is best illustrated in Fig. 1.

It now becomes necessary to provide means for throwing the plunger into its valve plug releasing position when the plug 10 is to be

moved into a position to permit the passage of gas through the device. Such means is provided in the form of a lever 28 which is pivoted upon the removable pin 29, having 5 the threaded head 30 connected to the block-like projection 16, and formed with the operating thumb piece 31 and the plunger engaging finger 32 which is notched at 33 to permit movement of the extremity of this 10 finger farther through the bore 17 than would normally be permitted by the wall 34 of the opening 35 formed for the finger 32. It will be noted that the lever 28 pivots through a horizontal plane and that the valve 15 plug operating lever or handle 27 also travels through a horizontal plane elevated in respect to the plane of movement of the lever 28. In moving the valve plug operating lever 27 into a valve opening position, therefore, the thumb piece 31 of the lever 28 may 20 be engaged by the thumb of the hand operating the lever 27 and movement of the hand in one direction will cause the plunger body 19 to be moved out of the recess 24 and the 25 valve plug 10 rotated into its gas passing or opened position.

It is to be understood that the form of this invention herewith shown and described is to be taken as a preferred example of the 30 same, and that various changes in the shape, size, and arrangement of parts may be re-

sorted to without departing from the spirit of the invention or the scope of the subjoined claim.

Having thus described the invention, we 35 claim:—

The combination with a gas cock including a body formed with a longitudinal gas passage, and a rotary plug having a rigid handle extending laterally from one end thereof and adapted to project to one side of the body when the plug is positioned to close said passage, of a spring pressed latch bolt arranged longitudinally of the body and normally engaged with said plug to prevent rotation thereof from closed to open position, and a thumb lever operatively connected at its inner end with the latch bolt and projecting to the other side of the body, said thumb lever being arranged to be engaged 40 at its outer end by the thumb of the hand grasping the plug handle and to be pushed thereby for release of the latch bolt, the thumb lever and the handle being movable in the same direction about their axes for releasing the latch bolt and opening the plug, respectively. 45

In testimony whereof we affix our signatures.

JOHN BALTHASAR.
HERMAN GENTZ.
